(57) **CLAIM**

The ornamental design for a toilet bowl, as shown and
described.

DESCRIPTION

FIG. 1 is a perspective view of front, right and top plan side of
a toilet bowl showing our new design;

FIG. 2 is a front view thereof;

FIG. 3 is a rear view thereof;

FIG. 4 is a top plan view thereof;

FIG. 5 is a bottom view thereof; and,

FIG. 6 is a right side view thereof; the left side view being
mirror image thereof.

The portions of the article in broken lines are shown for
illustrative purposes only and form no part of the claimed
design.
